US00D848727S

(12) **United States Design Patent** (10) **Patent No.:** **US D848,727 S**
(45) **Date of Patent:** **** May 21, 2019**

(54) **MISTING UMBRELLA HANDLE**

(71) Applicant: **Raj Rao**, Newport Coast, CA (US)

(72) Inventors: **Raj Rao**, Newport Coast, CA (US);
Andrew Namminga, Newport Beach,
CA (US)

(73) Assignee: **Raj Rao**, Newport Coast, CA (US)

(**) Term: **15 Years**

(21) Appl. No.: **29/614,255**

(22) Filed: **Aug. 17, 2017**

Related U.S. Application Data

(63) Continuation of application No. 29/612,854, filed on Aug. 4, 2017.

(51) **LOC (11) Cl.** **03-03**

(57) **CLAIM**

The ornamental design for a misting umbrella handle, as shown and described.

DESCRIPTION

FIG. 1 is a perspective view of a misting umbrella handle; FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a perspective view of the mister umbrella handle shown in use with environment.

The broken lines depict portions of the article and environment that form no part of the claimed design.

1 Claim, 5 Drawing Sheets
